UNITED STATES PATENT OFFICE.

NATHAN H. ROBINSON, OF BRAINTREE, MASSACHUSETTS.

WRENCH.

Application filed April 8, 1924. Serial No. 704,954.

This invention pertains to wrenches and more particularly to wrenches having relatively movable jaws.

Wrenches of this type are employed in performing a great variety of mechanical operations frequently involving use in difficultly accessible and restricted places where it is practically impossible to employ both hands for manipulating and adjusting the wrench parts, and the principal object of the present invention is to provide a wrench of the type referred to having its parts so designed that the user may readily adjust the jaws of the wrench even in the most restricted situations without necessitating disengagement of the jaws from the work and by the employment of but one hand, the wrench being under complete control of the user throughout the adjusting operation.

Further objects are to provide a wrench of the character described in which adequate force may readily be applied for adjusting the jaws without the assistance of another wrench or similar tool; to furnish means by which the jaws may be secured positively in adjusted position if desired; and to embody the several features of improvement in a simple and durable construction which may be produced without difficulty and at low cost.

For purposes of illustration, I have herein disclosed my invention as embodied in a pipe or Stillson wrench, such exemplifications being shown in the accompanying drawings, in which:

Fig. 1 is a fragmentary side elevation of a pipe wrench embodying the invention;

Fig. 2 is an end elevation of the wrench shown in Fig. 1 viewed from its right hand end as illustrated in said figure; and

Fig. 3 is a longitudinal section substantially on the line 3—3 of Fig. 2.

Referring to the drawings, the numeral 1 indicates the fixed jaw of the wrench, such jaw being provided if desired with a hardened face 2. The fixed jaw is provided with an elongate rigid shank 3, preferably angular in cross section, furnished near its rear end with a pair of spaced substantially parallel ears or flanges 4 and 5. These ears or flanges may be integral with the shank if desired or as here illustrated may consist of plates secured to the opposite faces of the shank 3 by means of rivets 6.

The numeral 7 indicates a sleeve-like holder having a lateral offset member 8 which is disposed between the ears 4 and 5 and is pivotally secured to the latter by means of a pin 9. For best results this pin is arranged adjacent to that end of the offset 8 nearest to the fixed jaw 1. At a point adjacent to its opposite end the offset 8 is provided with a pocket 10 in which a spring 11 is seated. This spring bears against the adjacent face of the shank 3 and thus tends to swing the holder in a clockwise direction about the axis of the pin 9.

A handle 12 is journaled to turn freely in the sleeve-like holder 7. The forward end of the handle is furnished with a flange 13 which bears against one end of the holder, while a collar 14 is secured to the handle at the opposite end of the holder by means of a set screw, the flange and collar preventing axial movement of the handle relatively to the holder. The collar 14, or the flange 13 if preferred, is provided with a plurality of circumferentially spaced openings 15 either of which may be brought into alignment, by rotation of the handle, with an opening 16 in the end of the sleeve 7. When so aligned, a pin 17 having a head 18, may be passed through the aligned openings to prevent further rotation of the handle. Preferably the pin 17 is screw-threaded and the holes 15 are threaded to receive the pin, thus minimizing danger of loss of the pin. As a further or alternative safe guard, the pin may be attached to the handle by means of a chain or its equivalent.

The handle is provided with an axial internally screw-threaded bore 19 extending rearwardly to any desired distance from its forward end. The externally screw-threaded stem 20 of the movable jaw 21 of the wrench engages the threaded bore 19 of the handle. As here shown the stem or shank 20 and the movable jaw 21 are integrally united but it is within the scope of the invention to form these parts as separate elements connected in any suitable manner. Preferably the movable jaw 20 is furnished with a slot 22 for the reception of the edge of the shank 3 of the fixed jaw, such shank serving properly to guide the movable jaw as it advances or retreats from the fixed jaw.

In use the fixed and movable jaws 1 and 21 are placed upon opposite sides of the pipe,

- rod, or other work to be manipulated and by rotating the handle 12 the movable jaw may be advanced into firm engagement with the work whereupon the wrench is manipulated in the usual manner to turn or hold the work. Preferably the exterior surface of the handle 12 is knurled or roughened to permit the user to obtain a firm grip thereon, the elongate extended surface of the handle permitting great force to be applied in moving the jaw 21 toward and from the work. Such force may be applied without removing the tool from the work and by the employment of one hand only, making the implement very convenient for use in restricted situations, or where, as for example when the wrench is being used overhead, it is difficult to employ both hands at the same time.
- 20 The wrench thus devised is of very rigid construction, comprising but few parts, and these are simple and easy to manufacture. The engaging threaded portions of the stem and handle are unusually long, thus prolonging the life of the implement and permitting great force to be applied without breaking down or injuring the screw threads, while the capability of ready manipulation and adjustment by the use of one hand is a manifestly desirable advantage.

I claim:

1. A wrench comprising a movable jaw having an integral elongate screw threaded shank, said jaw having a guide groove in its rear face, a substantially cylindrical handle having an internally screw threaded bore in one end to receive the shank of the movable jaw, said handle having a fixed flange at the end in which the bore is formed, a holder mounted upon the handle to turn freely relatively thereto, one end of said holder bearing against said flange, a collar secured to the handle and bearing against the other end of the holder to retain the latter

in operative position axially of the handle, the last-named end of the holder having a plurality of socket openings therein, a pin carried by the collar, said pin being engageable with any selected one of said openings to lock the handle against rotation, a fixed jaw having a substantially straight and smooth shank slidably engaging the guide groove in the rear face of the movable jaw, and means attaching the shank of the fixed jaw to the holder.

2. A wrench comprising a movable jaw having an integral elongate externally screw threaded shank, said jaw having a guide element on its rear face, a substantially cylindrical one-piece handle having an integral radial flange at one end and an internally screw threaded axial bore extending inwardly from said end and adapted to receive the threaded shank of the movable jaw, a holder having a journal opening for the reception of the handle, one end of said holder bearing against the radial flange, a collar secured to the handle and bearing against the opposite end of the holder, releasable locking means for preventing relative rotation of the handle and holder, a fixed jaw having an integral elongate shank provided with an element engaging the guide element on the rear face of the movable jaw, parallel spaced ears projecting from the shank of the fixed jaw adjacent to the end thereof, a lug projecting from the holder into the space between said ears, a pivot pin extending through said lug and ears to connect the fixed jaw to the holder, and a spring interposed between the end of the shank of the fixed jaw and holder, such spring tending to tilt the fixed jaw about said pivot pin as an axis.

Signed by me at Boston, Massachusetts, this 25th day of March, 1924.

NATHAN H. ROBINSON.
